US0D1100301S

(12) **United States Design Patent** (10) **Patent No.:** **US D1,100,301 S**
(45) **Date of Patent:** **** Oct. 28, 2025**

(54) **LIGHT FIXTURE**

(71) Applicant: **Zhongshan Mingcai Intelligent Lighting Technology Co., Ltd,**
Zhongshan (CN)

(72) Inventor: **Shuangfei Song**, Guangdong (CN)

(73) Assignee: **Zhongshan Mingcai Intelligent Lighting Technology Co., Ltd,**
Zhongshan (CN)

(**) Term: **15 Years**

(21) Appl. No.: **29/984,765**

(22) Filed: **Jan. 15, 2025**

(51) LOC (15) Cl. **26-05**

(52) U.S. Cl. **D26/72**
USPC .....

(58) **Field of Classification Search**

(57) **CLAIM**

The ornamental design for a light fixture, as shown and described.

DESCRIPTION

FIG. 1 is a perspective view of a light fixture showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the light fixture that form no part of the claimed design.

1 Claim, 8 Drawing Sheets
